CUTTER BLADE HOLDER

Bernard Tewelow, Wilmington, Del., and Solomon Tewelow, Philadelphia, Pa.

Application July 26, 1932, Serial No. 624,728

1 Claim. (Cl. 30—25)

Our invention relates to improvements in cutter-blade holders, and is especially directed to an improved holder for receiving and holding razor blades so the latter may be useful as knives or cutters after they have served their purpose as a razor blade.

One object of our invention is to provide an improved holder of such construction that the blade may be attached thereto so as to form a knife or to form a scraper, and

Another object is to provide an improved blade holder having a detachable handle and so constructed that when the handle is being attached to form a knife the parts will be automatically adjusted to their proper relative positions to clamp the blade between them with one cutting edge of the blade entirely concealed to provide protection against accidental injury to the operator.

The invention is illustrated in the accompanying drawing, wherein,—

Fig. 1 shows the improved holder in perspective with a blade attached thereto so as to form a knife, the same being associated with a strip of fabric which is being cut.

Fig. 2 illustrates, on an enlarged scale, a longitudinal section through the blade and clamp-members and also through the engaging end of the handle.

Fig. 3 is a view of the device taken on the line 3—3 of Fig. 2, with the greater portion of one of the two clamping members broken away to show the blade in clamped position.

Fig. 4 illustrates the holder in perspective but with the clamping members and blade attached to the handle so as to form a scraper, and

Fig. 5 shows an enlarged sectional detail through the same as viewed on the line 5—5 of Fig. 4.

In the drawing, the numeral 8 designates the handle which has a short externally screw-threaded stem 9 projecting from one end thereof and which, at the opposite end, is provided with a central internally screw-threaded socket 10. At the outer end this socket is gradually enlarged, which enlargement has a tapered annular clamping wall 11, for a purpose that will presently be explained.

Our improved holder employs, in addition to the separate handle, two blade-clamping and guard plates 12 and 13 respectively. We use the expression, clamp and guard in defining these two plates, because they actually cover the blade they clamp, so that only one cutting edge of that blade

is exposed, as will hereinafter more clearly appear.

The combined clamp and guard plate 12 has an inner flat clamping face 14 and at one end has a circular externally-threaded stem 15.

This plate 12 also has two inclined lugs 16 punched therefrom so as to project at the inner flat-face side thereof, and it will be noted, that said lugs both incline in the same direction.

Midway between the lugs 16, the plate 12 also has a circular opening 17 therethrough from the outer to the inner side thereof.

Particular attention is called to the fact that the lugs 16 and the circular opening 17 of plate 12 are all located in a longitudinal line nearer the bottom edge 18 of the plate than to the top edge 19 thereof. This is important for reasons that will presently be explained.

The guard and clamp plate 13 also has a flat inner face, and at the handle-engaging end is provided with a projecting end-lug 20 which has converging inclined upper and lower edges 21. The inclination of these edges 21, is such that the narrower end of the lug will enter the socket 10 of the handle while the upper and lower inclined edges 21 thereof will engage the tapered wall 11 of said handle-socket.

While the plate 12 also has a tapered edge construction, as can be seen in Figs. 1 and 4, those edges do not have the function of wedging 30 in the handle-socket, as they are slightly closer from top to bottom, thus permitting the edges 21 of lug 20 to certainly engage the socket-wall before the tapered edges on the plate 12 will engage that wall.

The purpose of certainly engaging the edges 21 of lug 20 of plate 13 before the tapered edges on plate 12 make such engagement in the socket, is, so that the plate 13 will be moved forward slightly with respect to plate 12, to effect a locking-together of the plates, as will presently be explained.

The plate 13 has two spaced-apart slots 22, each of which has a wall 23 that inclines in a direction that corresponds to the inclination of the lugs 16 that project from the plate 12 so that by a slight forward sliding of the plate 13 over plate 12, the inclined walls 23 of plate 13 are seated under the inclined lugs 16 of plate 12 and the two plates are thereby drawn toward each other.

This slight lengthwise movement of plate 13 is caused by the inclined edges 21 of lug 20 on plate 13 engaging the tapered wall 11 of the handle-socket.

55

The plate 13 further has a circular opening 24 between the two slots 22 and the interior of this opening 24 is provided with screw-threads.

When the two plates 12 and 13 are engaged by 5 the handle and locked together, the openings 17 and 24 are aligned.

The razor-blade 25 is of the double-edge type in that its two longitudinal edges 26 are cutting-edges. This blade has a central perforation 27 10 and two slightly elongated perforations 28 fore and aft of the central perforation.

All of these perforations 27 and 28 in the blade are longitudinally centered between the two cutting edges 26, whereas the lugs 16 and opening 15 17 in plate 12 and the slots 22 and opening 24 of plate 13 are all located longitudinally in a line nearer the bottom than the top edges of said plates 12 and 13.

The object in thus locating the lugs and slots 20 in the plates 12 and 13 is, that when the blade 25 is clamped between the inner flat faces of said plates with the lugs 16 of plate 12 passing through the perforation 28 of the blade, the latter will be held between the plates with the lower 25 cutting edge 26, only, exposed, while the upper cutting edge will be entirely covered by said plates, which will form a guard to prevent injury to a person's fingers while handling the device.

It will be noted that when the handle is attached to the end of the plates, as in Figs. 1, 2 30 and 3, no clamping means or other device projects in front of the forward corner 29 of the blade so that the holder and blade may be inclined to a marked degree to enable a line marked 35 on a piece of fabric to be readily traced, as when cutting out patterns.

It will also be noted that when it is desired to use the holder as a scraper, the handle may be reversed, end-for-end, and the threaded stem 9

thereof passed freely through opening 17 of plate 12, then through the central opening 27 of the blade and finally screwed into the threaded opening 24 of plate 13, and thus securely clamp the blade between the two plates, as shown in Figs. 4 and 5. 5

Having described our invention, we claim,—

A holder for razor blades having in combination a handle provided at one end with a longitudinally-extending internally-threaded socket 10 with a tapered annular clamping wall and at the opposite end having a projecting threaded stem, two disconnected and separable clamping-plates,—one having two spaced-apart inclined lugs punched therefrom so as to project at the 15 inner side thereof and also having an intermediate opening while the other of said disconnected plates is provided with spaced slots each with an inclined wall to receive said punched-out inclined lugs and an intermediate screw-threaded opening, one of said disconnected plates also having a threaded stem at one end to enter the longitudinally-extending internally-threaded handle-socket and the other of said two plates having an end lug with inclined edges to engage 20 the annular clamping wall of the handle-socket whereby the two plates with a blade between them may be drawn toward each other to clamp the blade when the plate having the lug with the inclined edges engages the clamping wall of the handle-socket, or, said plates with a blade between them may be attached to the handle by passing the stem of the handle through the intermediate opening of the lug-plate then through 25 the blade and screwing said stem into the intermediate threaded opening of said other plate. 30 35
